UNITED STATES PATENT OFFICE.

WILLIAM J. NEIDIG, OF CHICAGO, ILLINOIS.

TYPE-WRITING MACHINE.

1,218,688.

Specification of Letters Patent. Patented Mar. 13, 1917.

Application filed June 30, 1916. Serial No. 106,919.

To all whom it may concern:

Be it known that I, WILLIAM J. NEIDIG, a citizen of the United States, residing at Chicago, in the county of Cook and State 5 of Illinois, have invented certain new and useful Improvements in Type-Writing Machines, of which the following is a specification.

The objects of my invention are to supply 10 the operator of a type-writing machine with a means for throwing sheet-position indicating devices into disuse irrespective of their operative position, and to supply him with a quick and convenient means for re- 15 tracting the paper-feeling element in sheet-controlled indicating devices from the paper path, or from contact with the sheet, or from any other non-retracted position, either or both.

20 I attain my several objects by the mechanism illustrated in the accompanying drawings, in which—

Figure 1 is an end view of one embodiment of my invention, with parts of the 25 typewriter carriage frame broken away; Fig. 2 is an end view of another embodiment of my invention, with parts of the typewriter carriage and index rim broken away; and Fig. 3 is a cross-section of Fig. 30 2 on the line 3—3.

Similar symbols of reference refer to similar parts in the several drawings.

The usual carriage frame is indicated at 1, the platen at 2 (Fig. 2), the platen arbor 35 at 3, the platen head at 4, the paper table at 5. Other typewriter parts, not necessary to be shown herein, are or may be as in practice.

The embodiment of my invention shown 40 in Fig. 1 is described as follows: Attached upon the typewriter is a sheet-controlled indicator for indicating the position and approach of the end of the sheet, such for instance as is shown and described in various embodiments in my United States Patents Nos. 1,053,919 to 1,053,928 inclusive. A convenient form for present illustrative purposes consists of the index rim 7, lightly pressed against the end of the platen by the 45 pressure of collar 8 upon disk spring 9 seated upon inside shoulder 10 of the index rim. Rim 7 is supplied with a downstanding portion 11, inside of which the platen head is loosely journaled. Collar 8 is held in lateral position upon the hub portion of 50 the platen head by a set-screw. Carriage

frame 1 bears the inwardly projecting pin 12 upon which is journaled the light arm 13 having an inwardly extending portion 14 that constitutes a paper-feeler. This inwardly extending paper-feeler has a path through slot 15 in paper table 5. Journaled upon pin 16 on arm 13 is a trip lever 17; the construction is such as to permit the trip lever to bend idly upon the said pin in 60 one direction but not in the other, so as to permit free backing-up of the index rim. A light coiled spring 18 on the hub 19 of arm 13 bears at one end upon pin 20 on frame 1 and at the other upon an outwardly 65 extending portion of pin 16, and tends to hold paper-feeler 14 out of slot 15 and against the platen in retracted position, with trip-lever 17 lying in the path of projection 21 on rim 7. A pointer 22 to co- 70 operate with the indices and markings on index rim 7 is attached upon the carriage frame under screw 23.

In operation the sheet is inserted in usual manner down the paper table and advanced 80 by turning the platen-roll. This action revolves index-rim 7, bringing projection 21 into engagement with trip-lever 17. Further revolution of the platen causes trip-lever 17 to bring paper-feeler 14 down upon the 85 sheet, where it is detained by the sheet, and through it rim 7, until the end of the sheet passes from over slot 15. When this occurs feeler 14, no longer detained by the sheet, passes into the slot, and index rim 7, fric- 90 tionally driven, takes up movement with the platen bringing its indices, or other indicating means as shown and described in said patents, into operative action.

My present invention consists of a means 95 for throwing indicating devices such as the one just described into disuse in any position of the mechanism, and also of a means for conveniently retracting the paper-feeler (in cases where the indicator makes use of 100 such an element) from a non-retracted position so as to facilitate handling the sheet. Journaled upon carriage frame 1 by means of inwardly projecting pin 24 is throw-off lever 25, manually actuated by an upwardly 105 extending portion 26. Lever 25 has an inwardly extending portion 27, which engages with a downwardly extending portion 28 of arm 13 when actuated downwardly while said arm 13 is in non-retracted position. A 110 stop 29 on said portion 28 conveniently limits the movement of said throw-off lever in

one direction, and the outwardly-extending thumb portion 30 acts against the upper edge of carriage frame 1 to limit it in the other. A spring 31, conveniently attached upon frame 1 by screws 32, presses lever 26 against the carriage frame so as to hold it either in engaged or disengaged position, an outward bend 33 midway of the operative portion of the spring assisting in this action. The illustration shows throw-off lever 25 in its retracted position, with portion 27 lying out of the path of portion 28 of said arm 13 previously described.

In operation the device works as follows: Suppose the operator has entered the sheet and paper-feeler 14 has been moved down into contact therewith and the operator changes his mind and decides to throw the indicating mechanism into disuse, or desires to readjust his sheet on the paper table and wishes to retract the paper-feeler for the moment. He merely throws lever 26 toward the platen arbor, thereby through parts 27 and 28 raising paper-feeler 14 into retracted position against the platen, and the same movement serves to lock the arm 13 against further operative movement, and through it and trip-lever 17 and projection 21 to detain index rim 7 in stationary position and disuse. And if the operator then or later wishes to resume the use of the indicating mechanism, all he has to do is to throw lever 26 away from the platen arbor and the indicating mechanism is at once free to operate.

The indicating mechanism shown in Figs. 2 and 3 is described as follows: Carriage frame 1 has an upwardly extending portion 1¹, upon which is attached the inwardly projecting pin or stud 12¹. Journalized upon this pin is the light sheet-metal part 13¹, consisting of a laterally extending connecting portion (indicated at 13²) and two end portions. The outer end portion bears pin 16¹, upon which is journalized trip-lever 17¹ extending into the path of projection 21. A paper-feeler 14¹ extends downwardly from portion 13² and has a path into a slot in paper table 5. Stud 12¹ bears a projection 20¹ (Fig. 3), against which presses one end of a light coiled spring 18¹, the other end of which bears against part 13¹ in such manner as to tend to hold paper feeler 14¹ retracted against the platen. Projection 21 engages upon trip-lever 17¹ and through it moves paper-feeler 14¹ into its slot in the paper table, just as in the case of trip-lever 17 and feeler 14 of Fig. 1, and the resultant action upon rim 7 is the same and the indicating action is the same.

The throw-off and retracting device is described as follows: Pin or stud 12¹ is seated against a shouldered collar 24¹ (Fig. 3), upon which is journalized a lever 25¹ having an inwardly extending portion 27¹ adapted

to engage with an upwardly extending portion 28¹ of part 13¹. This lever 25¹ is supplied with an inwardly projecting pin 34, and frame extension 1¹ with another pin 35, between which a spring 31 acts expandingly. Two stops or lugs 29¹ on lever 25¹ conveniently coöperate with pin 35 to limit the movements of lever 25¹ aforesaid. The device is shown in the illustrations as in locked position, with the indicating mechanism locked in disuse.

Its action is as follows: If the operator desires to use the indicating mechanism he presses the thumb portion 30¹ of lever 25¹ toward the platen arbor, thereby compressing spring 31 between pins 34 and 35 until pin 34 passes over the center, after which spring 31 throws lever 25¹ still farther until the forward lug 29¹ rests against pin 35. Portion 27¹ is now beyond the path taken by portion 28¹ when the paper-feeler is thrown into its slot by projection 21 and the indicator is left free to operate. If the operator thereafter desires to retract the feeler, or to throw the indicating mechanism into disuse, or both, he will press thumb portion 30¹ away from the platen arbor, thereby bring part 27¹ against part 28¹, and so retract the feeler, after which the spring 31 will hold the parts thus, being stronger than the light pressure exerted by the frictionally driven rim 7 through trip-lever 17¹ and projection 21, whereupon rim 7 will thereafter be held in stationary position, in disuse.

I expect that embodiments of my invention based on that shown in Figs. 2 and 3 will be more widely used in practice, and where it can be adapted that is the form I prefer.

It will be understood that the action of both parts 27 and 27¹ as described herein is ultimately an action detaining the platen-actuated rim 7 and thereby preventing it from performing its usual functions in the indicating mechanism, and that either part can be moved into detaining position in any position of rim 7, and that rim 7 is not necessarily detained in the position in which it stands when either part 27 or part 27¹ is thus moved into detaining position but may have an additional forward movement thereafter or may be pushed backwardly thereby, and that the detaining action of the said parts 27 and 27¹ is communicated through trip-levers 17 or 17¹ and projection 21 as a mere matter of convenience. It will also be understood that parts 27 and 27¹ perform the additional function of retracting paper-feelers 14 and 14¹ from their slots or other non-retracted positions, although in the indicating mechanisms shown in the figures the springs 18 and 18¹ act to retract the feelers upon the passing or withdrawal of projection 21, said springs not being used in all types of indica-

tors. It will also be understood that although my invention will preferably be used with the types of indicators referred to herein, I do not regard it as necessarily limited 5 to such use.

I claim as my invention:

1. In a typewriting machine, in combination, a platen for advancing the sheet, a paper-feeler, indicating means under the control of said feeler, and a retractor adapted to move the paper-feeler out of the paper path, said retractor operated manually.
2. In a typewriting machine, in combination, a platen, a paper feeler, indicating means under the control of said feeler, a retractor for said feeler adapted to be operated manually, and means for maintaining said feeler in retracted position.
3. In a typewriting machine, in combination, a platen, a paper-feeler, indicating means under the control of said feeler, a retractor for said feeler, and a spring for holding said retractor in retracting position.
4. In a typewriting machine, in combination, a platen, indicating means including a detainable member actuated from said platen, and a detent adapted to detain said member in disuse and manually operable in every position of said indicating means.
5. In a typewriting machine, in combination, a platen, indicating means actuated from said platen, a throw-off adapted to throw said indicating means into disuse, and a spring for controlling the position of said throw-off.
6. In a typewriting machine, in combination, a platen, an index rim yieldingly actuated from said platen, a detent adapted to detain said index rim in disuse, and a spring adapted to hold said detent in detaining position, said detent manually operated.
7. In a typewriting machine, in combination, a platen, an index rim frictionally

driven from the platen, a manually operable detent for said index rim, a spring for holding said detent in detaining position, and stopping means for limiting the movement of said detent.

50

8. In a typewriting machine, in combination, a platen, a paper-feeler, an index rim detainably driven from the platen and connected to press said paper-feeler into the paper path, and a manually operable detent 55 connected to actuate said rim backwardly until said paper-feeler lies in retracted position out of the paper path.

9. In a typewriting machine, in combination, a platen, a paper-feeler, an index rim 60 detainably actuated from the platen under the control of said feeler, and a throw-off device adapted to retract and hold said paper-feeler from the paper path and to detain said index rim in disuse.

65

10. In a typewriting machine, in combination, a platen, a paper-feeler, an index carrier actuated from the platen under the control of said feeler, a throw-off device adapted to retract said feeler from the paper path 70 and hold said index carrier in disuse, and a spring for maintaining said device in operative position.

11. In a typewriting machine, in combination, a platen, a paper-feeler, an index rim 75 frictionally driven from the platen and having a projection thereon, a trip-lever in the path of said projection and operative upon said paper-feeler, a throw-off device operable to cause said trip-lever to bear backwardly against said projection and also connected to hold said paper-feeler out of the paper path, and a spring for holding said throw-off device in detaining position 80 against the pressure of said index rim.

WILLIAM J. NEIDIG.
